CLAIM

The ornamental design for a gaming machine, as shown and described.

DESCRIPTION

This application incorporates by reference the following applications in their entirety: U.S. patent application Ser. No. 29/698,015, filed Jul. 12, 2019, and U.S. patent application Ser. No. 29/698,516, filed Jul. 17, 2019. All disclosure and subject matter, including all figures, of these applications are specifically incorporated by reference in this application as if set forth fully herein.

FIG. 1 is a front perspective view of a gaming machine showing our new design according to a first embodiment; FIG. 2 is a front elevation view thereof;

FIG. 3 is a right side elevation view thereof;

FIG. 4 is a left side elevation view thereof;

FIG. 5 is a top plan view thereof;

FIG. 6 is a front perspective view of a gaming machine showing our new design according to a second embodiment;

FIG. 7 is a front elevation view thereof;

FIG. 8 is a right side elevation view thereof;

FIG. 9 is a left side elevation view thereof; and,

FIG. 10 is a top plan view thereof.

The dashed broken lines in the figures illustrate portions of the gaming machine that form no part of the claimed design.
